LID FOR FRYING PANS

Gunnar Horgard, Trondheim, Norway, assignor to Sintef,
Trondheim, Norway, a research foundation of Norway

Filed Nov. 29, 1965, Ser. No. 88,252

Claims priority, application Norway June 1, 1965

Term of patent 14 years

(Cl. D44—1)

FIG. 1

FIG. 2

FIG. 3

FIG. 4

FIG. 5

FIG. 1 is a top plan view of a lid for frying pans, showing my new design;

FIG. 2 is a side elevational view taken from the right of FIG. 1;

FIG. 3 is a rear elevational view;

FIG. 4 is a bottom plan view; and

FIG. 5 is a front elevational view.

I claim:

The ornamental design for a lid for frying pans, as shown.
